UNITED STATES PATENT OFFICE.

ISAIAH HALL, OF ASTON, BIRMINGHAM, ENGLAND.

MELTING-FURNACE.

1,161,047.

Specification of Letters Patent. Patented Nov. 23, 1915.

Application filed October 19, 1914. Serial No. 367,455.

To all whom it may concern:

Be it known that I, ISAIAH HALL, subject of the King of Great Britain, residing at Whitehouse street, Aston, Birmingham, in the county of Warwick, England, have invented a new and useful Improvement in Melting-Furnaces; and I do hereby declare the following to be a full, clear, and exact description of the same.

10 My invention relates to melting furnaces, more especially such as are adapted for remelting used metal, cleansing it, and casting it into ingots and has for its object to provide improvements relating to such furnaces with the object of facilitating their use.

Referring to the accompanying drawings, Figure 1 is a section of the upper part of the furnace showing means for reciprocating the mixing member. Fig. 2 is a plan showing also the valve regulating lever. Fig. 3 shows the general arrangement of the furnace. Fig. 4 shows a view at right angles to that shown in Fig. 3, the mixing lever being omitted to show more clearly the operation of the valve in a preferred arrangement of the same. Figs. 5 and 6 show a pivoted gate or valve which may be located upon the end of the pouring spout of the furnace. Fig. 7 shows a preferred arrangement of the valve.

Such a furnace is filled with metal and heated by gas or otherwise from below. Some suitable arrangement must be made 35 for allowing the metal to flow from the furnace to the molds or like when required, and for greater convenience the furnace is provided with a regulating valve 1 located centrally and a reciprocating stirring device 2 attached to a sleeve 3 or the like surrounding the stem 4 of the said valve 1. The upper surface of the metal pot is enclosed by a cover 5 which may have sliding doors for the admission of metal for charging the pot and may have an arrangement of pipes and flues as described in my prior U. S. Patent No. 1117667, issued Nov. 17, 1914.

The stem 4 of the valve 1 I may take 50 straight through the center of the cover 5 providing a stuffing box 6 or like arrangement therein, and its upper end is connected directly or by a short link to a lever 7 pivoted to a bracket 8 disposed on the cover.

The sleeve 3 of the stirring device which 55 may be of any of the forms in my prior U. S. Patent No. 1117667, issued Nov. 17, 1914, may terminate in a loose collar (to permit rotation) or a fixed flange, as shown at 9 on the drawing, or lugs to which I attach preferably two rods 10 which pass also through gas tight joints in the cover, one being disposed upon either side of the valve stem and operating lever. In some cases three, four, or more rods may be employed, 65 but the sleeve arrangement is preferred as it tends to keep all dirt and dross from getting to the valve.

A pair of vertical supports 12 are provided with flanges 13 and bolted to the 70 domed cover of the furnace near its outer edge, forming a support to the upper end of which is pivoted the operating lever 14. A projection 15 is formed upon one of the supports, slightly below the level of the 75 pivot, through which a bolt 16 is adapted to pass which engages slot 17 in the form of an arc of a circle having the pivot for its center, said slot being formed in a similarly shaped portion 18 projecting 80 upon the upper and lower sides of the lever. A washer and wing nut 19 upon the bolt enable the lever to be secured in any desired position. The inner part of the lever extends approximately to the center of the 85 furnace and terminates in a downwardly extending forked end to which a link bar 20 is pivoted, the lower end of the said bar being pivoted between two lugs 21 formed on the upper side of connecting plate to 90 which the rods 10 connected to the mixing member are attached.

The lever may be formed in two parts or more if desired, for instance, adjacent to the portion in which the slot is formed, a socket 95 22 may be formed internally screw threaded for the reception of a length of pipe or other suitable handle 23.

It will be clear that this invention obviates to a large extent the necessity for holes 100 and slots through which air is likely to obtain access to the upper surface of the material in the pot, while at the same time making suitable provision for the working of the regulating and stirring or mixing apparatus.

The stuffing box may be conveniently in the form of a pair of screwed sleeves 24 in-

serted from opposite ends of the holes and having asbestos packing 25 between their abutting extremities.

It will be clear that the slot 17 in conjunction with the stationary pin or bolt 16 limits the motion of the lever to the extent of the arc and consequently limits the stroke of the mixer to this predetermined extent.

Referring more particularly to Figs. 3, 4, 10 5 and 6 the lever 7 is pivoted to the bracket 8 upon the cover 5 over the top of the melting pot. Upon the opposite side of the cover 15 a second bracket 26 is provided in which are formed holes 27, (a corresponding hole being in some cases formed in the lever), and in this manner by placing the peg or pin 28 through the holes in the bracket the lever may be retained at a height corresponding to the positions of the different 20 holes. In this manner the valve may be raised and the lever retained by means of the peg to such a height as to give the required flow at the pouring spout. As the molds or the like are filled, however, it is 25 desirable to check the flow momentarily while fresh molds are placed in position or the mold 29 is inverted.

Figs. 5 and 6 represent a form of stop or gate which may be fixed upon the pouring 30 spout by means of the screw-threaded portion 30 forming part of the bracket 31 to which the gate proper 32 is pivoted at 33. The gate may be provided with a wooden

handle 34, and may rest in a lip or like 35, by means of which it is pressed against the 35 bracket 31, so checking the flow of metal.

Fig. 7 shows the valve to an enlarged scale, the valve proper 1 being shown upon the seating 36 which is retained in the bottom of the furnace by means of the collar 40 or nut 37. In order to prevent the dross or scum upon the surface of the metal from getting past the valve to the pouring spout I may provide a shield 38, provided with 45 holes 39 upon the seating of the valve, and this may be screwed into position as shown upon the drawings.

What I claim is:—

A melting furnace comprising in combination a melting pot; a cover over said pot; a valve within said pot; a valve rod operatively connected to said valve; a lever upon said cover connected to said valve rod; a substantially gas-tight joint in said cover through which said valve rod passes; a valve seating in the bottom of said pot; a pouring spout to which access is given by said valve; and a perforated shield surrounding said valve seating.

In testimony whereof, I have signed my name to this specification in the presence of two subscribing witnesses.

ISAIAH HALL.
